FIG. 2

INVENTOR

Lloyd V. Lewis
By his attorney

UNITED STATES PATENT OFFICE.

LLOYD V. LEWIS, OF EDGEWOOD BOROUGH, PENNSYLVANIA, ASSIGNOR TO THE UNION SWITCH & SIGNAL COMPANY, OF SWISSVALE, PENNSYLVANIA, A CORPORATION OF PENNSYLVANIA.

CIRCUIT-CONTROLLER.

1,272,972.

Specification of Letters Patent. Patented July 16, 1918.

Application filed August 10, 1915. Serial No. 44,761.

To all whom it may concern:

Be it known that I, LLOYD V. LEWIS, a citizen of the United States, residing at Edgewood borough, in the county of Allegheny and State of Pennsylvania, have invented certain new and useful Improvements in Circuit-Controllers, of which the following is a specification.

My invention relates to circuit controllers, and particularly to slow-acting circuit controllers, such for example as slow-acting relays.

I will describe one form of slow-acting relay embodying my invention and will then point out the novel features thereof in claims.

In the accompanying drawing, Figure 1 is a view, partly diagrammatic and partly perspective, showing one form of relay embodying my invention. Fig. 2 is a view showing in section the construction of the left end of connecting rod R.

Similar reference characters refer to similar parts in both views.

Referring now to the drawing, reference character M designates a motor, here shown to be of the two-phase induction type and comprising stator coils f, f, within which a rotor 1 is mounted to rotate on a shaft 2.

Motor M is adapted to rock a shaft 5 through the medium of a pinion 3 fixed on shaft 2 and meshing with a segmental gear 4 attached to shaft 5. A weight 6, which is provided to bias shaft 5 to turn counter-clockwise, is adjustably mounted on a screw

7 which is rigidly secured at right angles to shaft 5 by means of a sleeve 8. Counter-clockwise movement of shaft 5 is limited by means of a screw 9 which is passed through

a threaded hole in a fixed member 10 (preferably part of the relay casing not shown) and adapted to engage a tongue 11 on gear 4. Similarly, clockwise movement of shaft 5 is limited by the engagement of one of the

arms 12 of gear 4 with a fixed stop 13. When the motor is deenergized shaft 5 assumes, under the influence of counterweight 6, a position such that tongue 11 rests against the tip of screw 9. When the motor

is energized it rocks shaft 5 clockwise until stop 13 prevents further movement, and then holds the shaft in this position. It is evident that by turning screw 9 in the fixed member 10 it is possible to vary the initial

position of shaft 5, so that the amount of

angular movement of the shaft can thus be adjusted.

Shaft 5 is adapted to rock a member 15, pivoted on a shaft 16, through the medium of a crank arm 24 fixed to shaft 5 and a resilient connecting device R. This connecting device comprises a tubular member 18 and a rod 17, one end of which is adapted to slide in member 18 as shown in Fig. 2. The rod 17 and member 18 terminate respectively in jaws 23 and 22, which are pin-connected respectively to crank 24 and member 15. Surrounding the rod 17 is a helical tension spring 19 which serves to hold the end of shaft 17 in the tubular member 18. One end of the spring is threaded into helical grooves 20 on the exterior of member 18, and the other end of the spring is fixed to rod 17 by means of an adjustable clamp 21. When shaft 5 is turned by motor M, spring 19 is stretched due to the movement of crank arm 24. On account of the large number of turns of the spring it follows that the spring tension varies but slightly with a small elongation, and it may be said that as long as the spring is stretched member 15 is acted upon by an approximately constant force, tending to turn it clockwise.

Member 15 is adapted to drive a braking mechanism which as here shown comprises a disk 26 of aluminum or other non-magnetizable electroconductive material adapted to rotate in the field of two permanent magnets p, p. It is understood, however, that any other suitable braking mechanism may be used. To drive the braking mechanism I provide a ratchet 28 adapted to be rotated through the medium of a pawl 29 pivoted on an arm 30 attached to member 15. Disk 26 is rotated by ratchet 28 by means of a train of gears G interposed between the ratchet and the disk. According to the laws of electromagnetic induction, eddy currents are set up in the disk, as it is rotated in the field of the magnets. The eddy currents consume energy and oppose the rotation of the disk with a torque which depends upon the speed of rotation of the disk, provided the magnetic field remains unchanged. If friction is neglected, the torque applied by member 15 must be completely counter-acted by the retarding torque of disk 26. But, as pointed out hereinbefore, the torque on member 15 is constant, hence the retarding torque of the disk

is constant. It follows that the speed of rotation of the disk must be constant, so that when spring 19 has been elongated by the motor M, member 15 rocks with a uniform velocity until brought to rest by means hereinafter described.

As member 15 rocks it operates electrical contacts in the following manner. An arm 50 of member 15 is bifurcated at its end to receive a link 33; the link being loosely secured to arm 50 by means of a pin 34 passed through a slot 35 in one end of the link 33. The other end of the link is pin-connected to a rocker arm 36 which is riveted to a bridge 37 adapted to swing on pivots 38. Bridge 37 is generally adapted to operate a plurality of contacts, but for purposes of simplicity I have shown only one. This contact comprises a finger 39 mounted on the bridge by means of insulating studs 40. Contact tips 41 and 42 are riveted to finger 39 and are adapted to engage fixed contact blocks 43 and 44 respectively. The bridge is biased by a weight 51 so that contact tip 41 normally engages block 43. The bridge may be turned by the engagement of pin 34 with the top of slot 35 so that tip 42 engages block 44. Weight 51 normally holds contact 41-43 firmly closed. Constant pressure is secured for contact 42-44 by residual tension of spring 19 after the mechanism has been operated when the relay is energized.

The operation of the relay will be readily understood from the foregoing description of the mechanism. When motor M is energized it rocks shaft 5 at once from its initial position to its final position (wherein arm 12 of segmental gear 4 engages member 13) and in this manner spring 19 is stretched and causes member 15 to turn slowly in a clockwise direction with a uniform velocity. As the time required for motor M to complete its motion is a small portion of the total time required to operate the device, variations in the time of movement of motor M such as would be caused by variations in voltage, therefore affect the time of operation of the relay to a much smaller extent than if spring 19 were not used. Pin 34 of member 15 slides upwardly in slot 35 of link 33 so that after an interval of time it engages with the upper end of the slot and causes bridge 37 to open the lower or back contacts and close the upper or front contacts. The front contacts are held closed until motor M is deenergized, whereupon, due to the action of weight 6, shaft 5 is turned counter-clockwise so that connecting device R causes member 15 to turn in the same direction. This return movement of member 15 is not impeded by the braking disk 26 because the pawl 29 rides freely on ratchet 28. Thus pin 34 is moved downwardly to permit the lower or back contacts to be closed by the action of the weight 51.

It is to be noted that the parts moved in the reverse direction by action of counter-weight 6 do not include any portion of the braking device, hence, excessive friction in the braking device will not result in holding the contacts closed after the motor M is deenergized.

It will be noted that the relay which I have described is slow-acting only while it is picking up. Its time of release is no longer than that of a relay of the ordinary type. This is of great advantage in many instances, for example in railway signaling systems where relays are used to control the signals. Sometimes it is desirable that such a signal shall not indicate "proceed" until after the lapse of a definite period of time after the relay controlling the signal has been energized: whereas it is of greatest importance that the signal shall be released from its proceed indication immediately after the relay is deenergized. A relay embodying my invention is admirably suited for such uses, it being necessary only to control the proceed indication circuit of such a signal by a front contact of the relay.

After the relay has once been adjusted, the time of pick-up again can easily be changed by means of screw 9 the head of which is preferably protruded beyond the relay casing. As pointed out hereinbefore, the angle through which shaft 5 is moved when the motor is energized can be adjusted by means of screw 9. This means, then, that the normal position of pin 34 in the slot 35 is varied accordingly, so that the time required for the pin to reach the top of the slot is also varied. Since the contacts are not operated until pin 34 engages the upper end of slot 35 it follows that the pick-up period of the relay varies according to the amount of time required for pin 34 to reach the upper end of slot 35 from its initial position. It will be noted that pin 34 moves upward in slot 35 with a constant velocity (provided other adjustments of relay are unaffected) and that the variation of time interval which elapses before pin 34 reaches the upper end of slot 35 is affected only by the changes of the initial position of pin 34 in slot 35.

Although I have herein shown and described only one form of circuit controller embodying my invention, it is understood that various changes and modifications may be made therein within the scope of the appended claims without departing from the spirit and scope of my invention.

Having thus described my invention, what I claim is:

1. A circuit controller comprising a movable member, means for exerting forces on said member to move it in opposite directions, a braking device, means interposed between said member and said braking de-

vice for operatively connecting the two when the member is moved in one direction but for permitting unretarded movement of the member in the opposite direction, a contact device biased to one controlling position, and means interposed between the movable member and the contact device for moving the latter to another controlling position during the latter part of the movement of the member in the direction in which it is operatively connected with the braking device.

2. A circuit controller comprising a movable member, means for exerting forces on said member to move it in opposite directions, a braking device, means interposed between said member and said braking device for operatively connecting the two when the member is moved in one direction but for permitting unretarded movement of the member in the opposite direction, a contact device biased to one controlling position, and a pin and slot connection between said movable member and said contact device for moving the contact device to another controlling position during the latter part of the movement of the member in the first mentioned direction and for permitting return of the contact device in response to its bias during the early part of the movement of the said member in the other direction.

3. A circuit controller comprising a movable member, a spring attached to said member, means for storing energy in said spring whereby the spring exerts a force on said member tending to move the latter, a braking device, means interposed between said movable member and said braking device for operatively connecting the two when the movable member is moved by the energy stored in the spring but for permitting unretarded movement of the said member in the opposite direction, a contact biased to one controlling position, and means interposed between said contact and said member for moving the contact in opposition to its bias to another controlling position during the latter part of the movement of the movable member in response to the force exerted thereon by said spring.

4. A circuit controller comprising two movable members, connecting means interposed between said members and comprising a spring, means for moving one of said members in such direction as to store energy in said spring whereby the spring then exerts a force on the other of said members, braking means for retarding the movement of the second member in response to the force exerted thereon by said spring, and a contact device controlled by said second member.

5. A circuit controller comprising a movable member biased in one direction, means for moving said member in opposition to its

bias, a second movable member, connecting means interposed between said members for positively moving the second member when the first member moves in response to its bias, said connecting means comprising a spring in which energy is stored by the first member when the latter is moved in opposition to its bias whereby the spring then exerts a force on the second member, braking means for retarding the movement of the second member in response to the force exerted thereon by the spring, and a contact device controlled by said second member.

6. A circuit controller comprising a movable member biased in one direction, means for moving said member in opposition to its bias, a second movable member, connecting means interposed between said members for positively moving the second member when the first member moves in response to its bias, said connecting means comprising a spring in which energy is stored by the first member when the latter is moved in opposition to its bias whereby the spring then exerts a force on the second member, a braking device, connecting means interposed between the second member and said braking device for operatively connecting the two when the second member is moved by the energy stored in the spring but for permitting unretarded movement of the second member in the opposite direction, a contact device biased to one controlling position, means interposed between said second member and the contact device for moving the latter to another controlling position in opposition to its bias during the latter part of the movement of the second member under the influence of the energy stored in the said spring and for permitting return of the contact device in response to its bias during the early part of the return movement of the second member in the other direction.

7. A slow acting circuit controller comprising a motor, a pivotally mounted member, resilient mechanism for rocking said member uniformly by said motor, a magnet, a disk adapted to rotate in the field of said magnet, mechanism for rotating said disk by said member when said member is being rocked by said motor, and contacts adapted to be operated by said member.

8. A slow acting circuit controller comprising a motor, a shaft, means for biasing said shaft to turn in one direction, means for rocking said shaft by said motor in the opposite direction, a crank arm on said shaft, a pivotally mounted member, a resilient connection between said crank arm and said member whereby said member may be rocked by said motor, a magnet, a disk adapted to revolve between the poles of the magnet, a ratchet, a pawl on said member for driving the ratchet when the member is being rocked by said motor, means for ro-

- tating the disk by the ratchet, a contact comprising a block and a finger biased away from said block, a link operatively connected at one end to said finger, a slot near the 5 other end of the link, and a pin on said pivotally mounted member adapted to slide in said slot, so that the said finger is not operated to engage the said block until after said pin has engaged one end of said slot.
- 10 9. A circuit controller comprising a movable member biased in one direction, resilient means for moving said member in opposition to its bias, slow-acting means for causing a slow movement of said member by said 15 resilient means but not for retarding the return movement of said member, an electromagnetic device for storing a definite amount of energy in said resilient means, and a contact controlled by said member.
- 20 10. A circuit controller comprising a mov-

able member biased in one direction, resilient means for moving said member in opposition to its bias, slow-acting means for causing a slow movement of said member by said resilient means but not for retarding the return movement of said member, an electromagnetic device for storing a definite amount of energy in said resilient means, a contact, and a lost motion connection between said member and said contact for 25 moving the contact after the member has made a predetermined movement in response to the action of said resilient means.

In testimony whereof I affix my signature in presence of two witnesses.
